UNITED STATES PATENT OFFICE.

JOHN PRICE WETHERILL, OF SOUTH BETHLEHEM, PENNSYLVANIA.

MAGNETIC SEPARATOR.

SPECIFICATION forming part of Letters Patent No. 708,185, dated September 2, 1902.

Application filed August 26, 1901. Serial No. 73,297. (No model.)

To all whom it may concern:

Be it known that I, JOHN PRICE WETHERILL, a citizen of the United States, residing at South Bethlehem, county of Northampton, 5 State of Pennsylvania, have invented certain new and useful Improvements in Magnetic Separators; and I do hereby declare the following to be a full, clear, and exact description of the invention, such as will enable others skilled in the art to which it appertains to make and use the same.

My invention relates to the separation of magnetic material from relatively less magnetic material or diamagnetic material associated therewith, the heads representing the portions which are susceptible to magnetic attraction and separation by means of the magnets employed in the apparatus and the tailings representing the residue of non-magnetic or relatively non-magnetic material contained in the mixture of ore or like substance treated.

My invention is designed principally for the treatment of "fines" and of material of relatively low magnetic susceptibility or permeability, although it will be understood that the fundamental features of construction and operation shown and described are capable of use in similar apparatus intended for the treatment of material of any suitable size or mesh and even of highly-magnetic material, such as magnetite and the like.

The main or characteristic feature of the invention consists in supplying the material to be separated to interpolar spaces or gaps formed between opposing magnet-poles immersed in a suitable water tank or vat, whereupon the heads are detained in said interpolar spaces until the accompanying tailings 40 have been washed away, and continuously removing the detained heads by means of a scraper as they are freed from their associated tailings, the heads and tailings being collected in separate receptacles or places of deposit and collection. I have devised several forms of apparatus embodying this fundamental principle of operation, one of which is illustrated in the accompanying drawings. Others are illustrated in additional applications for Letters Patent of the United States, filed of even date herewith, Serial Nos. 73,298 and 73,299.

In the accompanying drawings, Figure 1 represents a top plan view of an apparatus embodying my invention. Fig. 2 represents 55 a side elevation thereof with the containing tank or vessel shown in section. Fig. 3 represents a cross-sectional view, partly in elevation.

Similar letters of reference indicate similar parts throughout the several views.

Referring to the drawings, A represents a containing tank or vessel adapted to receive a supply of water maintained at about the level indicated by the dotted line in Figs. 2 65 and 3. Within said water-tank A project the opposing poles *a* of two electromagnets B, so arranged as to form a complete magnetic circuit having two interpolar spaces or gaps constituting magnetic fields of high 70 concentration, due to the pointed or wedge-shaped form of the polar projections. Supply-hoppers C, provided at their lower ends with the feed-rollers *b*, supply the fines or other material to be separated to the aprons 75 *c*, pivoted, as shown, and adjustable by means of the notched links *e* or otherwise, the material being directed from said aprons into the interpolar spaces or gaps. At opposite ends of the tank are erected the rotatory 80 shafts D, one of which is adapted to be driven from a belt-pulley E or the like. These shafts carry grooved pulleys F, which pulleys are spanned by a belt G, carrying a series of scraper-blades *d*, of brass or other 85 non-magnetic material, said blades having a shape or configuration corresponding to that of the wedge-shaped pole-pieces, so as to substantially fit the space between said pole-pieces, as will more fully appear on reference 90 to Fig. 3. Perforated pipes H, having regulating-valves—as, for instance, *h*—are designed to direct a series of water-jets into the interpolar spaces and to this end may conveniently be located just within and slightly 95 above the interpolar spaces. Immediately below and outside of the interpolar spaces are located the receiving-hoppers I, having suitable gates, as shown, and immediately within said interpolar spaces are located the inclines 100 *J*, which themselves terminate in valved hoppers *K*, as shown in Fig. 2. At one end of the interpolar spaces are located the hoppers *L*, designed for the reception of the magnetiz-

able portions or heads, as will hereinafter more fully appear.

The operation of the apparatus is as follows: The fines or other material of suitable mesh to be separated are fed from the hoppers C by means of the feed-rollers b and are directed by the adjustable aprons c into the interpolar spaces or gaps. At the same time the belt G and its scraper-blades are caused 5 to move in the direction indicated by the arrows, Fig. 1, and the pipes H direct a series of water-jets through the interpolar spaces. The magnetic particles are thereupon attracted and detained by the magnet-poles, and 10 while thus detained the non-magnetic or relatively non-magnetic material associated therewith is separated by the dissolving action of the water and the impact of the water-jets and is washed away, falling for the most part 15 into the hoppers I. The scraper-blades, operating within the interpolar spaces, progressively remove the attracted material by causing it to move toward and into the receiving-hoppers L, some portions, however, falling 20 upon the inclines J and being received in the hoppers K. It will of course be understood that the operation is intended to be a continuous one, the feed of material from the hoppers C being maintained as nearly constant as possible during the travel of scrapers 25 and the play of the water-jets.

Having thus described my invention, what I claim is—

1. A magnetic separator comprising magnet-poles spaced apart to form an intervening gap traversed by the magnetic lines of force, means for feeding into said gap the material to be separated, means for washing out 30 the non-attracted particles from the particles

detained by magnetic attraction in said gap, and a scraper for removing the attracted particles, said scraper having projections which scrape both pole-pieces; substantially as described.

45 2. A magnetic separator comprising an upper magnet-pole and a lower magnet-pole spaced apart to form an intervening gap traversed by the magnet lines of force, means for feeding into said gap the material to be separated, means for washing out the non-attracted particles from the particles detained by magnetic attraction in said gap, and a scraper having its path of movement through the gap, and provided with a series of scraper-blades 50 extending transversely of the gap in such manner as to scrape both pole-pieces; substantially as described.

3. A magnetic separator, comprising an upper magnet-pole and a lower magnet-pole spaced apart to form an intervening gap, said magnet-poles being pointed or wedge-shaped at their ends to concentrate the lines of force across the gap, means for feeding into said gap the material to be separated, means for 60 washing out the non-attracted particles from the particles detained by magnetic attraction

in the gap, and a scraper having its path of movement through the gap and provided with scraper-blades of a configuration conforming to the outline of the pole ends, substantially 70 as described.

4. A magnetic separator, comprising magnet-poles separated by an intervening gap traversed by the magnetic lines of force, means for feeding into said gap the material 75 to be separated, a jet-pipe for expelling the non-attracted particles from the particles detained by magnetic attraction in said gap, and a scraper for removing the attracted particles, said scraper having projections which 80 scrape both pole-pieces; substantially as described.

5. A magnetic separator, comprising magnet-poles separated by an intervening gap traversed by the magnetic lines of force, 85 means for feeding into said gap the material to be separated, a jet-pipe for expelling the non-attracted particles from the particles detained by magnetic attraction in said gap, a scraper for removing the attracted particles, 90 and a water vat or tank in which the magnet-poles and jet-pipe are immersed; substantially as described.

6. A magnetic separator, comprising an upper magnet and a lower magnet, of substantially U shape in cross-section and having their opposing poles so related as to form with the cores a magnetic circuit with two gaps, means for feeding into said gaps the material to be separated, jet-pipes for expelling the 95 non-attracted particles from the particles detained by magnetic attraction in the gaps, and a scraper consisting of an endless belt provided with a series of scraper-blades having a path of movement successively through 100 the gaps and extending transversely of the gap in such manner as to scrape both pole-pieces; substantially as described.

7. A magnetic separator, comprising an upper magnet-pole and a lower magnet-pole 110 spaced apart to form an intervening gap, means for feeding into said gap the material to be separated, a vat or tank containing water in which the magnet-poles are submerged, a scraper operating within the gap, a jet-pipe 115 having its jet-openings directed through the gap, laterally-disposed hoppers to receive the non-attracted particles, and an end hopper to receive the attracted particles as they are conveyed to it by the scraper; substantially as 120 described.

8. A magnetic separator, consisting of upper and lower U-shaped magnets whose poles are so arranged as to form a magnetic circuit with two gaps, outlying hoppers for supplying to said gaps the material to be separated, jet-pipes whose jets are directed through the gaps on the opposite side to the feed, an endless belt carrying scraper-blades having a path of movement successively through the 125 gaps, laterally-disposed hoppers to receive the non-attracted particles, and an end hop- 130

per to receive the attracted particles as they are conveyed to it by the scraper; substantially as described.

9. A magnetic separator, provided with an interpolar gap, means for feeding into said gap the material to be separated, a water-containing tank within which the separator-poles are submerged, a jet-pipe whose jets are directed through the gap, and means for removing the particles detained in the gap by magnetic attraction; substantially as described.

10. A magnetic separator, provided with an interpolar gap, means for feeding laterally

into said gap the material to be separated, a water-containing tank within which the separator-poles are submerged, a jet-pipe whose jets are directed laterally through the gap, and a longitudinally - moving scraper; substantially as described.

In testimony whereof I affix my signature 20 in presence of two witnesses.
